CHAIR OR SIMILAR ARTICLE

Adrian M. Pearsall, Forty Fort, Pa., assignor to Craft Associates, Inc., Wilkes-Barre, Pa., a corporation of Pennsylvania

Filed Mar. 5, 1965, Ser. No. 84,119

Term of patent 14 years

(Cl. D15—1)

The dominant features of my design reside in those portions shown in full lines.

I claim:

The ornamental design for a chair or similar article, as shown and described.
